UNITED STATES PATENT OFFICE

161,835

FLUID EVACUATOR

Harold M. Hanks, San Francisco, Calif.

Application March 15, 1950, Serial No. 8,541

Term of patent 14 years

(Cl. D52—2)

To all whom it may concern:

Be it known that I, Harold M. Hanks, a citizen of the United States of America, residing at San Francisco, in the county of San Francisco and State of California, have invented a new, original, and ornamental Design for a Fluid Evacuator, of which the following is a specification, reference being had to the accompanying drawing, forming a part thereof, wherein:

Fig. 1 is a view in perspective showing the front of the evacuator; and

Fig. 2, a view in perspective showing the rear of the evacuator.

I claim:
The ornamental design for a fluid evacuator, as shown.

HAROLD M. HANKS.
